RUDOLPH G. MULLER, OF IRVINGTON, NEW JERSEY

HAT MAKING MACHINE

Application filed December 1, 1931. Serial No. 578,283.

This invention relates to improvements in hat making machines of the kind known to the industry as tip-stretchers.

In tip stretching machines as heretofore constructed, the vertically reciprocated and angularly adjustable stretcher fingers converge at their inner or upper ends upon a tip cushion. This tip cushion is supported within a cavity in the bottom of the hub from which said stretcher fingers radiate, and usually comprises a disc-like body of resilient material, such as soft vulcanized rubber. Said tip cushion is axially aligned with the stationary ribbed former of the machine, upon which the hat body under treatment is supported subject to the action of the stretcher fingers, which are vertically reciprocated in relation to said former and the hat body supported thereby. The tip cushion is thus opposed to the apex of the former, and, being relatively soft, cushions and protects the hat body tip against injury during tip stretching co-operation of stretcher fingers and former. In the machines as heretofore provided, no provision has been made for readily and quickly removing the tip cushion for replacement when it has become worn or soiled, which is of more or less frequent occurrence; and it has been heretofore necessary to practically disassemble the stretcher finger mechanism in order to accomplish such replacement of the tip-cushion. Such necessity results, not only in loss of service of the machine for appreciable time periods, but also involves loss of the operator's time, with consequent reduction in his capacity for finished work output; and, furthermore, disturbs the adjustment of the stretcher fingers so that readjustment of the same is necessary before operation of the machine can be resumed.

Having these objections in mind, it is the principal object of this invention to provide a novel and relatively simple means for detachably mounting tip cushions for quick and easy removal and replacement, without necessity for either dismantling the stretcher finger mechanism or disturbing given adjustments thereof desired to be maintained.

This invention has for a further object

to provide a novel means for pivoting the stretcher fingers, whereby a maximum pivotal bearing support thereof is possible, resulting in a stronger and more rigid support of said fingers, and the elimination of undesirable loose play and vibration thereof during operative cooperation thereof with the former of the machine, while at the same time affording a very compact assembly of the stretcher finger mechanism as a whole.

Other objects of this invention, not at this time more particularly enumerated, will be understood from the following detailed description of the same.

An illustrative embodiment of this invention is shown in the accompanying drawings, in which:—

Fig. 1 is a fragmentary front elevation of the upper portion of a tip stretching machine provided with stretcher finger means according to this invention; Fig. 2 is a vertical longitudinal section through the stretcher finger means, taken on line 2—2 in Fig. 1, showing the novel tip cushion holding means supporting a tip cushion in operative assembled relation to the stretcher finger means; Fig. 3 is a view similar to that of Fig. 2, but showing the tip cushion holding means released to permit removal and replacement of the tip cushion; and Fig. 4 is a horizontal section, taken on line 4—4 in Fig. 3, but drawn on an enlarged scale.

Similar characters of reference are employed in the above-described views, to indicate corresponding parts.

Referring to said drawings, the reference character 5 indicates the cross-head from which the stretcher finger means is suspended, said cross-head being carried upon a pair of slide rods 6, vertically reciprocable in guide bearings 7 connected with the framework of the machine; all in the customary manner whereby the stretcher finger means is vertically reciprocated relative to a former 8, to operatively engage and stretch a hat body 9 supported upon the latter.

The stretcher finger means comprises a spindle 10 having an externally threaded lower portion 11. Connected with the lower end of said spindle 10 is a hub-member 12

55

60

65

70

80

85

90

95

100

having a central through opening 13 to receive a removable tip cushion 14. Said hub member 13 is connected to said spindle, preferably as an integral structure, by means of 5 a yoke portion 15 which spans the opening 13; said yoke portion having a transverse open passageway 16 therethrough, above the upper face or side of the hub member, and arranged to communicate with the upper end 10 of said hub opening 13. The underside of said hub member 12 is provided with a downwardly open annular recess or channel 17, bounded on its inner side by a wall 18 surrounding the central opening 13 and on its outer side by a wall 19.

The reference character 20 indicates the several stretcher fingers which are equi-spaced around and which radiate from the hub member 12 in downward and outward 20 angular extension therefrom. Each stretcher finger 20 is pivoted to swing on a horizontal axis at right angles to the vertical plane thereof, such axis being disposed in a plane radial to the vertical axis of the hub member 25 12 and off-set ninety degrees from the radial plane of the stretcher finger. To this end fulcrum pins or bolts 21 are provided, the same each having a threaded portion 22 to screw into internally threaded openings 23 30 in the outer wall 19 of the hub member; the free ends of said pins entering into openings 24 provided in said inner wall 18 of the hub member, thus firmly supporting said fulcrum pins in and for extension between said hub 35 member walls and through annular recess or channel defined thereby. Integrally formed with and extending from the upper inner ends of said stretcher fingers 20 are arcuate arms 25 terminating in pivoting knuckles 26 40 which are journaled upon corresponding fulcrum pins 21, the arrangement thereof being such that said arms underlap one another. By this described arrangement for pivotally connecting the stretcher fingers 20 with the hub member 12, it will be apparent that a 45 comparatively long and substantial pivotal bearing support is provided therefor, to the end that loose play and lateral vibration of the fingers are eliminated and the same are 50 rigidly and strongly supported while nevertheless free to be adjustably swung inwardly or outwardly to accommodate the operation thereof to the particular size of hat body acted upon at any given time.

55 The means for adjusting the stretcher fingers to increase or decrease the angular spread thereof, comprises a nut member 27 threaded upon the externally threaded portion 11 of said spindle 10 for vertical adjusting movements thereon. The lower end of said nut member 27 is provided with a laterally projecting annular flange 28 upon which is seated a fulcrum plate 29 provided, in projecting extension from its periphery, with a plurality of bifurcate hinge knuckles 30.

Said hinge knuckles 30 correspond in number to the number of stretcher fingers 20 and are vertically aligned therewith. Links 31 are pivotally connected by their lower ends with the free end portions of said stretcher fingers 20, and are respectively pivoted by their upper ends to the respective hinge knuckles 30 of said fulcrum plate 29. A hand wheel 32 is secured to said nut member 27 above the fulcrum plate 29, whereby said nut member 70 may be turned to effect desired vertical movement thereof on the threaded portion 11 of the spindle 10, to thereby raise or lower, at will, said fulcrum plate; said nut member 75 being freely rotatable relative to the latter. Threaded upon said screw threaded portion 11 of the spindle 10 above the nut member 27 is a lock or jam nut 33 having a hand-wheel flange 34, the same being manipulatable relative to said nut member 27 to lock the same 80 in any given position to which it has been adjusted.

The stretcher finger means is connected with the cross-head 5 of the machine by passing the upper end of said spindle 10 upwardly therethrough and through a supporting collar 35 fixed to said cross-head; said spindle being secured against vertical displacement by a set-screw 36, or by any other suitable fastening means.

The upper inner ends of said stretcher fingers 20 are provided with terminal extensions 20' converging toward the lower open mouth of said hub opening 13, thus forming shoulders 20'' which underlie said opening 100 so as to abut the tip cushion 14 when the same is operatively mounted in said hub opening 13. The means for detachably mounting said tip cushion 14 in said hub opening 13, and in operative relation to said 105 stretcher finger shoulders 20'', so that the same may be easily and quickly removed and replaced at will without disturbing the stretcher finger connections or without disturbing the angular adjustment of said 110 stretcher fingers, comprises the following arrangement. Said spindle 10 is provided with an axial bore 37 extending therethrough, a portion (preferably the upper portion) of which is internally screw-threaded as at 38. Extending through said bore 37 and axially movable therein, by virtue of the threaded connection of an externally screw-threaded portion 39 thereof with said internal threads 115 38, is a stem 40. The upper outwardly projecting end of said stem 40 is provided with a squared head 41 for the application of a suitable wrench or key thereto for turning the same. Fixed to the lower end of said stem 40, preferably as an integral part thereof, is a disc-like backing member 42 for engagement with the tip cushion 14. Said backing member 42 possesses a diameter somewhat less than the internal diameter of said hub opening 13, whereby the former may be 120 125 130

easily moved into and out of the latter as occasion requires.

When in normal operative position, the tip cushion 14 is lodged within the hub member opening 13, so that its lower face abuts said shoulders 20" of the stretcher fingers. The tip-cushion, as thus disposed, is firmly secured in place against movement by screwing downwardly said stem 40 to carry said backing member 42 into said hub member opening 13 and in downwardly thrusting and holding engagement with the top of said tip cushion 14, as shown in Fig. 2 of the drawings.

Should it be desired to remove and replace the tip-cushion 14, the stem 40 is screwed upwardly to withdraw the backing member 42 from holding engagement with the tip-cushion and entirely out of the hub member opening 13, whereupon by using any rod-like implement, as 43 in Fig. 3, the tip-cushion may be pushed upwardly out of the top of said hub member opening 13, and into the transversely open passageway 16 of the yoke portion 15, as shown by full lines in said Fig. 3. After being thus raised clear of the hub member opening 13 in the described manner, the tip-cushion 14 may be thereupon thrust by the finger or otherwise sideways and out of said transverse passageway 16, as indicated by dot and dash lines in said Fig. 3, whereupon the same may be taken away. These operations are reversed when assembling a tip-cushion in the stretcher finger means as will be obvious.

From the above description it will be clear that the tip-cushion 14 may be easily and quickly removed and replaced, without necessity of dismantling the stretcher fingers 20 or even disturbing any given adjusted position of the same which may be desired to be continued or maintained.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

I claim:

1. In a machine of the kind described, stretcher means including a support and a plurality of stretcher fingers projecting angularly and radially from said support, said support having a central opening outwardly open at its upper and lower ends, a tip cushion disposed in said opening to abut converging inner end portions of said stretcher fingers, and releasable means for holding said tip cushion so disposed, said tip cushion being replaceably removable through the outwardly open upper end of said opening.
2. In a machine of the kind described,

stretcher finger means having a spindle for connecting the same with the machine including a hub member having an axial opening therethrough terminating upwardly in a laterally open passage, a tip cushion within said opening disposed to abut converging inner end portions of said stretcher finger means, and said tip cushion being replaceably removable from the upper end of said opening through said passage.

70

75

3. In a machine of the kind described, stretcher finger means having a spindle for connecting the same with the machine including a hub member having an axial opening therethrough terminating upwardly in a laterally open passage, a tip cushion within said opening disposed to abut converging inner end portions of said stretcher finger means, said tip cushion being replaceably removable from the upper end of said opening through said passage, and releasable means for holding said tip cushion in operative relation to said stretcher finger means.

80

85

4. In a machine of the kind described, stretcher finger means having a spindle for connecting the same with the machine including a hub member having an axial opening therethrough and a yoke member provided with a transversely open passageway communicating with the upper end of said hub member opening, a tip cushion within said hub member opening, said tip cushion being replaceably removable through the upper end of said hub member opening and through said transverse passageway, and releasable means for holding said tip cushion within said hub member opening.

90

95

5. In a machine of the kind described, stretcher finger means having a spindle for connecting the same with the machine including a hub member having an axial opening therethrough and a yoke member provided with a transversely open passageway communicating with the upper end of said hub member opening, a tip cushion within said hub member opening, said tip cushion being replaceably removable through the upper end of said hub member opening and through said transverse passageway, said spindle having a central bore, a stem vertically movable in said bore, and said stem having a backing member at its lower end to engage and hold said tip cushion within said hub member opening and in operative assembled relation to said stretcher finger means.

100

105

110

115

120

6. In a machine of the kind described, stretcher finger means having a spindle for connecting the same with the machine including a hub member having an axial opening therethrough and a yoke member provided with a transversely open passageway communicating with the upper end of said hub member opening, a tip cushion within said hub member opening, said tip cushion being replaceably removable through the upper

125

130

end of said hub member opening and through said transverse passageway, an axially movable stem in screw-threaded engagement with said spindle for vertical movement relative thereto, and said stem having a retractable backing member movable therewith across said passageway and into said hub member opening to hold said tip cushion within the latter and in operative assembled relation to said stretcher finger means.

7. In a machine of the kind described, stretcher means comprising a supporting spindle having a hub member, a plurality of stretcher fingers projecting angularly and radially from said hub member, said hub member having a central opening laterally open at its upper end, a tip cushion disposed in said opening to abut converging inner end portions of said stretcher fingers, said tip cushion being replaceably removable through the laterally open upper end of said opening, an axially movable manipulatable stem in screw-threaded engagement with said spindle for vertical movement relative thereto, and said stem having a retractable backing member movable therewith into said hub member opening to hold said tip cushion within the latter and in operative assembled relation to said stretcher fingers.

8. In a machine of the kind described, stretcher means comprising a supporting spindle having a hub member, a plurality of stretcher fingers projecting angularly and radially from said hub member, said hub member having a central opening laterally open at its upper end, a tip cushion disposed in said opening to abut converging inner end portions of said stretcher fingers, said tip cushion being replaceably removable through the laterally open upper end of said opening, an axially movable manipulatable stem in screw-threaded engagement with said spindle for vertical movement relative thereto, and said stem having a retractable backing member movable therewith into said hub member opening to hold said tip cushion within the latter and in operative assembled relation to said stretcher fingers, and means adjustably movable relative to said spindle and connected with said stretcher fingers for adjusting the angular spread of the latter.

9. In a machine of the kind described, stretcher means comprising a supporting spindle having a hub member provided with an annular downwardly open channel and a central opening outwardly open at its upper and lower ends, a plurality of stretcher fingers projecting angularly and radially from said hub member, pivot pins for each stretcher finger journaled in said hub member to extend through and transversely across said channel thereof to provide a pivotal axis for each stretcher finger disposed in a plane radial to the axis of said hub-member and off-set ninety degrees relative to the radial

plane of the stretcher finger, the upper inner ends of each finger having off-set arcuate arms terminating in pivoting knuckles rotatable on said pivot pins, means adjustably movable relative to said spindle and connected with said stretcher fingers for adjusting the angular spread of the latter, the inner upper ends of said stretcher fingers further having shoulder portions converging upon and underlying the lower open end of said hub member opening, and a tip cushion removably disposed in said hub member opening to abut said stretcher finger shoulders.

10. In a machine of the kind described, stretcher means comprising a supporting spindle having a hub member provided with an annular downwardly open channel, and a central opening laterally open at its upper end, a plurality of stretcher fingers projecting angularly and radially from said hub member, pivot pins for each stretcher finger journaled in said hub member to extend through and transversely across said channel thereof to provide a pivotal axis for each stretcher finger disposed in a plane radial to the axis of said hub-member and off-set ninety degrees relative to the radial plane of the stretcher finger, the upper inner ends of each finger having off-set arcuate arms terminating in pivoting knuckles rotatable on said pivot pins, means adjustably movable relative to said spindle and connected with said stretcher fingers for adjusting the angular spread of the latter, the inner upper ends of said stretcher fingers further having shoulder portions converging upon and underlying the lower open end of said hub member opening, a tip cushion within said hub member opening and replaceably removable through the laterally open upper end thereof, and releasable means for holding said tip cushion within said hub member opening and abutting said stretcher finger shoulders.

11. In a machine of the kind described, stretcher means comprising a supporting spindle having a hub member provided with an annular downwardly open channel, and a central opening laterally open at its upper end, a plurality of stretcher fingers projecting angularly and radially from said hub member, pivot pins for each stretcher finger journaled in said hub member to extend through and transversely across said channel thereof to provide a pivotal axis for each stretcher finger disposed in a plane radial to the axis of said hub-member and off-set ninety degrees relative to the radial plane of the stretcher finger, the upper inner ends of each finger having off-set arcuate arms terminating in pivoting knuckles rotatable on said pivot pins, means adjustably movable relative to said spindle and connected with said stretcher fingers for adjusting the angular spread of the latter, the inner upper ends of said stretcher fingers further having

shoulder portions converging upon and underlying the lower open end of said hub member opening, a tip cushion within said hub member opening and replaceably removable through the laterally open upper end thereof, and releasable means for holding said tip cushion within said hub member opening and abutting said stretcher finger shoulders, said latter means comprising an axially movable stem in screw-threaded engagement with said spindle for vertical movement relative thereto, and said stem having a retractable backing member movable therewith across said passageway and into said hub member opening to hold said tip cushion within the latter and in operative assembled relation to said stretcher finger means.

12. In a machine of the kind described, stretcher means comprising a supporting spindle having a hub member provided with an annular downwardly open channel and a central opening laterally open at its upper end, a plurality of stretcher fingers projecting angularly and radially from said hub member, pivot pins for each stretcher finger journaled in said hub member to extend through and transversely across said channel thereof to provide a pivotal axis for each stretcher finger disposed in a plane radial to the axis of said hub member and off-set ninety degrees relative to the radial plane of the stretcher finger, the upper inner ends of each finger having off-set arcuate arms terminating in pivoting knuckles rotatable on said pivot pins, means adjustably movable relative to said spindle and connected with said stretcher fingers for adjusting the angular spread of the latter, the inner upper ends of said stretcher fingers further having shoulder portions converging upon and underlying the lower open end of said hub member opening and a tip cushion within said hub member opening and replaceably removable through the laterally open upper end thereof, said spindle having a central bore, a stem vertically movable in said bore, and said stem having a backing member at its lower end to engage and hold said tip cushion within said hub member opening and in operative assembled relation to said stretcher finger means.

In testimony, that I claim the invention set forth above I have hereunto set my hand this 27th day of October, 1931.

RUDOLPH G. MULLER.
